UNITED STATES PATENT OFFICE.

HARRY V. MARSH AND HENRY J. STEPHENS, OF CHICAGO, ILLINOIS.

PLACARD.

Application filed February 23, 1923. Serial No. 620,764.

To all whom it may concern:

Be it known that we, HARRY V. MARSH and HENRY J. STEPHENS, citizens of the United States, residing at Chicago, in the county of Cook and State of Illinois, have invented a new and useful Placard, of which the following is a specification.

The present invention relates to placards and particularly to advertising placards used in direct association with objects of merchandise.

The primary object of the invention is to provide a new and novel means for connecting advertising matter with the object of merchandise to which it relates, and, secondarily, the object of the invention is to minimize the cost of material for such advertising matter by reducing the quantity of material required therefor.

These, and such other objects as may hereinafter appear are obtained by the novel combination, construction, and arrangement of the several parts of our device illustrated in the single sheet of drawing accompanying and made a part of this specification, and in which:—

Fig. 1 is a blank showing the general configuration of one form of the device; and

Fig. 2 is a perspective view showing one of our devices in operation.

Similar reference characters are used to designate identical parts in the specification which follows and in the drawing referred to above.

The device which we have invented is intended to be attached to a can or other container for merchandise in order to draw attention thereto. In its simplest form, the invention comprises a sheet of cardboard or similar material cut, except at its lowermost side, in any desired configuration.

Referring now to Fig. 1, it will be noted that the ordinal 1 is used to indicate the body of an advertising placard, and as hereinbefore indicated, it may be of any general form, and also, it may be printed on either or both sides.

At the base of body 1, is stamped or cut, a semicircular extension portion, which extension portion is vertically divided in order to provide two equal sized quarter sections 2^a and 2^b, hereinafter called tabs. The greatest dimension of the semicircular extension referred to, which is at the line of its division from the body 1, is equivalent to the diameter of a can of goods upon which

the device is used, as for example, the can 3 shown in Fig. 2, which can has the usual flange 3^a at its top. Scoring may be employed intermediate body 1 and tabs 2^a and 2^b in order to facilitate articulation or folding. If scoring is not desired, a printed or stamped line may be employed to indicate the point at which the folds should be made, although neither of such demarcations is absolutely necessary.

The body 1 is illustrated as having additional downward extensions which project along the side of the can 3, such extensions being termed ears and designated 4, and while desirable, are not wholly necessary. The ears 4 may extend along the sides of the can 3 any desired distance. When used, the internal portions of ears 4 are preferably parallel to one another and to the sides of the can 3.

At the inner and uppermost portion of each ear 4, oppositely disposed slots 5 are formed by stamping out a portion of the material. Slots 5 may be formed at the same time the blank hereinbefore referred to is made, and in conjunction with all of the other slits or cuts required, namely, the cut forming the tabs 2^a and 2^b, the slit separating said tabs, and the cuts producing ears 4. It is quite usual to cut or stamp out the entire blank or several blanks at a single stroke of a die directed against a single thickness of material, thus enabling the maker to produce blanks at a high rate of speed.

The purpose of slots 5 is to remove a portion of material so as to freely admit of the insertion of the flanged top section 3^a of can 3 within the ears 4, and at the same time to permit the tabs 2^a and 2^b, oppositely pointed, to rest upon the top of can 3 with their arcuate peripheral portions in engagement with the interior wall of flange 3^a.

After manufacture of the device, and the printing or decorating thereof, the device is taken in one hand and tabs 2^a and 2^b are folded at right angles, one backwardly and the other forwardly of the body 1. Holding up the tabs 2^a and 2^b with the fingers, can 3 is slipped into position upon blank 1 with the flange 3^a of the former registering in the cutaway portions 5 in ears 4. The tabs 2^a and 2^b are then released to rest upon can 3 within flange 3^a.

The space intermediate ears 4 is such that

frictional engagement between ears 4 and the sides of the can 3 results. Tabs 2^a and 2^b when released peripherally engage the inside portion of the flange 3^a on can 3 whereby to hold, vertically upright, body 1 of the device. Frictional engagement of the surfaces of tabs 2^a and 2^b upon the top of the can and the peripheral friction hereinbefore referred to and relating to the edges of said tabs, coupled with the frictional engagement of can 3 and the ears 4 and that of flange 3^a along the sides of the said ears, gives a snug and secure association between the can 3 and our device, and substantially prevents displacement thereof.

It is quite manifest that the tabs 2^a and 2^b are reversible and that when both surfaces of body 1 are printed, it too is reversible.

We claim:

1. An advertising device for use upon a flanged can or the like and provided from

a blank having a semicircular extension portion slit to provide equal sized tabs adapted to be folded in opposite directions, and having additional extension portions with 25 parallel interior edges cut away adjacent said tabs to provide an internal contour coinciding with the external contour of the said can.

2. An advertising device for use upon 30 cans having a rimmed top comprising a single sheet of material having a centrally disposed semicircular bottom extension divided to form, when folded, quadrants adapted to be seated in opposite directions 35 within said rimmed can top, and marginal extensions adjacent said centrally disposed extension for engaging the walls of said can at its diameter.

HARRY V. MARSH.
HENRY J. STEPHENS.
